CLAIM

The ornamental design for an aerodynamic flying disk, as shown and described.

DESCRIPTION

FIG. 1 is a perspective view of an aerodynamic flying disk showing my new design, a plurality of light sticks which can be inserted into a groove in the circumferential rim of the flying disk being shown in phantom;

FIG. 2 is a top plan view of the invention illustrated in FIG. 1;

FIG. 3 is a left elevational view of the invention illustrated in FIG. 2;

FIG. 4 is a right elevational view of the invention illustrated in FIG. 2;

FIG. 5 is a bottom plan view of the invention illustrated in FIG. 2;

FIG. 6 is a rear elevational view of the invention illustrated in FIG. 2; and,

FIG. 7 is a front elevational view of the invention illustrated in FIG. 2.

The broken lines shown in FIG. 1 are for illustrative purposes only and forms no part of the claimed design.
